UNITED STATES PATENT OFFICE.

GEORGE COOPER WARD, OF FORT WORTH, TEXAS.

PENHOLDER.

SPECIFICATION forming part of Letters Patent No. 657,370, dated September 4, 1900.

Application filed August 18, 1899. Serial No. 727,663. (No model.)

To all whom it may concern:

Be it known that I, GEORGE COOPER WARD, a citizen of the United States, residing at Fort Worth, in the county of Tarrant and State of Texas, have invented certain new and useful Improvements in Penholders; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to penholders; and it has for one object to provide a penholder in which the holder shall consist in part of a staff or barrel and in part of a loop or bow, so that in use the staff or barrel may lie lengthwise of the forefinger and preferably beneath the finger, while the loop or bow will receive the finger passing through same.

It has also for its object to provide a penholder which will consist in part of a staff or barrel and in part of a loop or bow, the two parts being hinged together, so that when folded one upon the other the pen or pen-point will be protected by the loop or bow, which will serve as a guard or shield for the same, and when unfolded the staff or barrel and loop or bow will constitute the penholder of the desired length for ease and comfort in writing.

To the accomplishment of the foregoing and such other objects as may hereinafter appear the invention consists in the construction and also in the combination of parts hereinafter particularly described and then sought to be specifically defined by the claims, reference being had to the accompanying drawings, forming a part hereof, and in which—

40 Figure 1 is a plan view of the penholder in its unfolded or open position. Fig. 2 is a plan view of the penholder in its folded or closed position, and Fig. 3 is a side view showing the position of the penholder when in use.

45 In the drawings the numeral 1 designates the staff or barrel portion of the penholder, adapted to carry the pen-point 2 and which may be any approved fountain-pen pattern or may be of any ordinary penholder style 50 without the fountain feature.

The numeral 3 designates the loop or bow of the penholder and which is pivoted or

hinged to the staff or barrel portion by the rivets or pins 4 passing through the prongs 5 of the loop or bow and into the body of the 55 barrel or staff or otherwise suitably hinged thereto. The loop or bow may be made of spring brass, nickel, or steel wire or other suitable metal, or may be hard rubber or other suitable substance, and when the prongs of 60 the loop 1 spread apart for the insertion of the staff or barrel they will exert sufficient elastic pressure on the barrel to hold the barrel and bow firmly together; but any other manner of holding the parts together so that 65 they will not be loose in their connection may be employed and be embraced within the scope of my invention.

In practice I prefer to make the length of the staff or barrel two and one-fourth inches 70 from end to end and the length of the loop or bow two and one-fourth inches from the end of the staff to the end of the bow when unfolded, thus making the length of the penholder four and one-half inches when in its 75 unfolded position ready for use. The length of the prongs to the loop or bow I prefer to make one inch from the point where they leave the bow or loop proper to their free ends, and the width of the bow at its widest point 80 I prefer to make one inch. The proportions stated have been found to be most suitable as a standard size for the parts of a penholder; but such proportions can be varied, as the invention is not limited to such dimensions. I 85 also prefer to slightly concave the inner faces of the prongs, so that they will conform to the shape of the staff or barrel in cross-section, but if the barrel and the prongs should be flattened at their meeting faces or otherwise formed 90 such change would be within the scope of the invention. I may also slightly deflect the loop or bow from a line parallel with the length of the barrel to make the penholder conform more nearly to the shape or contour 95 of the hand when in use. In use the staff and bow are opened or unfolded and the forefinger passed through the bow or loop, as illustrated in Fig. 3. This brings the staff or barrel directly under the forefinger with 100 its upper end terminating at or near the second joint of the finger, while one side of the loop or bow lies outside of the finger from that point up to about the knuckle of the

hand, thus conforming the penholder to the shape of the finger without throwing upon the finger any strain calculated to fatigue it or the hand and allowing freedom and ease to the fingers in the formation of letters, so that in the use of this penholder, with little use of the same, rapidity and legibility in handwriting can be easily acquired. When the penholder is not in use, the loop or bow portion can be folded upon the staff or barrel so as to bring the bow over the pen-point, as illustrated in Fig. 2 of the drawings, thus constituting a shield or guard to the pen-point and permitting the penholder to be carried in the pocket and without occupying much space. The bow or loop will also prevent the penholder from rolling when laid down on the desk.

I prefer to have the loop or bow formed so as to lie on both sides of the finger when the finger is inserted through the same, or on both sides of the staff or barrel when folded; but if a portion of one side of the loop should be omitted certain features of my invention would still be retained; but I consider it best to have the loop continued all the way around, as the penholder is then held steadier and better results are obtained.

I have illustrated and described what I consider to be the best form of the invention; but changes can be made therein and essential features of my invention still be retained. It is also obvious that the barrel portion of

the holder may be formed to receive a crayon or pencil instead of a pen-point and the holder used in the same way as when a pen-point is employed, and such change or substitution is within the spirit of the invention.

Having described my invention and set forth its merits, what I claim is—

1. A pencil or pen holder consisting of a staff or barrel formed at one end to receive a marking-point and at the opposite end provided with an elongated loop, the opposite walls of said loop diverging from each other next to the staff and then converging toward each other in the direction of the outer end of the loop, substantially as described.

2. As a new article of manufacture, a pencil or pen holder consisting essentially of an elongated loop adapted to receive the forefinger, and a staff or barrel formed at one end to receive a marking-point, said barrel being pivoted to one end of the loop so that when thrown outward the portion of the barrel beyond its pivotal connection to the loop will constitute a support for the forefinger passing through the loop and a bearing for the thumb and second finger in guiding the marking-point, substantially as described.

In testimony whereof I affix my signature in presence of two witnesses.

GEORGE COOPER WARD.
